[57] CLAIM

The ornamental design for a ladder top, as shown and described.

DESCRIPTION

FIG. 1 is a perspective view of a ladder top embodying our design;

FIG. 2 is a front top plan thereof;

FIG. 3 is a bottom plan view thereof;

FIG. 4 is a front elevational view thereof;

FIG. 5 is a rear elevational view thereof; and,

FIG. 6 is a left side elevational view thereof, the right side elevational view being a mirror image thereof.

The broken lines are for illustrative purposes only and form no part of the claimed design.
